UNITED STATES PATENT OFFICE.

WILLIAM N. M. ANDERSON, OF LOS ANGELES, CALIFORNIA.

GAFF OR GRAPPLING-HOOK.

1,031,903.

Specification of Letters Patent.

Patented July 9, 1912.

Application filed February 11, 1911. Serial No. 608,119.

To all whom it may concern:

Be it known that I, WILLIAM N. M. ANDERSON, a citizen of the United States, residing at Los Angeles, in the county of Los Angeles and State of California, have invented a new and useful Gaff or Grappling-Hook, of which the following is a specification.

This invention relates to an improved gaff 10 or grappling hook which is collapsible or capable of being folded into position in which the hooks are inturned beyond one end of the body so that the device can be conveniently carried in that position without danger of catching on other articles or 15 unfolded so as to be out-turned beyond the other end of the body when in position for use.

The main object of the invention is to 20 provide a gaff or grappling hook of this character and of simple and cheap construction and convenient and effective in operation.

The accompanying drawings illustrate the 25 invention, and referring thereto:—Figure 1 is a perspective view of the device in open or operative position. Fig. 2 is a perspective view of the device in closed or collapsed position. Fig. 3 is a section on line $\alpha^3-\alpha^3$ 30 Fig. 2. Fig. 4 is a partial elevation of adjacent portions of the gaff hook device, and a pole or handle therefor, with a connecting ferrule in section.

The device comprises a body 1 which may 35 be cylindrical in form and is provided at one end with means, such as an eye 2, for attachment to a line, and also, preferably, with means, such as a screw threaded portion 3, for attachment to a handle, as hereinbefore set forth. Said body 1 is formed with a plurality of longitudinal grooves 4, said grooves, for example, being three in number in case three hooks are to be provided. Hooks 5 of the usual form are provided with 45 eyes 6 extending in the grooves 4 and pivoted therein by pins 7 extending through said eyes and secured in the body 1 in the center thereof so as to enable the hooks to be placed in open position beyond one end of the body 50 or in closed position beyond the other end of the body. A removable plain collar or sleeve 8 is adapted to slide over the body 1 from either end and to engage with the shanks 5' of the hooks to hold the hooks in either open or closed position. The end por-

tions of the grooves 4 are inclined outwardly to the surface of the body 1 at each end, as shown at 9, so that when the shanks of the hooks are turned toward either end they will rest on the inclined end portions 9 of the grooves 4 of the body 1 at each end and will extend obliquely outward or at an angle to the axis of the body 1.

When the device is to be used, the hooks 5 are turned to the position shown in Fig. 1, 65 their shanks resting against the inclined end portions of the grooves 4 in the body 1 and the hooks 5 therebeyond, and the sleeve 8 is slipped over the body 1 and over the shanks 5' of the hooks, the obliquity of these shanks 70 or their inclination to the axis being comparatively slight, so that by forcibly pressing on the sleeve 8 it is caused to clamp or bind on the shanks and to engage tightly therewith and hold the hooks firmly in operative position.

When the device is to be collapsed or folded, the sleeve 8 is slipped off of the body 1, the hooks are folded back or reversed to the position shown in Fig. 2, their shanks engaging with the other ends of the grooves 4, and the hooks projecting therebeyond. The sleeve 8 is then slipped onto the body 1 in the opposite direction to that in which it was engaged for the operative position of 85 the device, the said sleeve engaging with the shanks 5' of the hooks to hold the hooks in collapsed or folded position.

The device may be used either with a line inserted through the eye 2, or with a handle 90 or pole 10 provided with a ferrule 11, see Fig. 4, screwed onto the screw threaded portion 3 on the body 1. The device is, therefore, adaptable for use either as a line or a handle gaff or grappling hook.

What I claim is:—

A gaff or grappling hook comprising a body having longitudinal grooves, each groove having outwardly inclined end portions extending to each end of the body, 100 pivot pins extending across the central portion of the grooves, folding hooks having eyes located in the grooves and through which the pivot pins are passed, and shanks adapted to fold against the outwardly inclined end portions of the grooves at one end of the body so that the hooks will extend therebeyond in closed position or be reversed so that the shanks will fold against the outwardly inclined end portions of the grooves 110

at the other end of the body and the hooks extend therebeyond in open position, and a removable plain sleeve adapted to slide on the body for securing the hooks by their shanks in either their open or closed position.

In testimony whereof, I have hereunto set

my hand at Los Angeles, California, this 4th day of February 1911.

WILLIAM N. M. ANDERSON.

In presence of—

ARTHUR P. KNIGHT,

FRANK L. A. GRAHAM.
